UNITED STATES PATENT OFFICE.

GEORGE F. WEISS, OF SPRINGFIELD, ILLINOIS, ASSIGNOR TO THE BLACK DIAMOND COAL-DRILL AND TOOL CO., OF SPRINGFIELD, ILLINOIS, A CORPORATION OF ILLINOIS.

MINER'S DRILL.

No. 871,013.

Specification of Letters Patent.

Patented Nov. 12, 1907.

Application filed February 5, 1907. Serial No. 355,961.

To all whom it may concern:

Be it known that I, GEORGE F. WEISS, a citizen of the United States, residing at Springfield, in the county of Sangamon and State of Illinois, have invented certain new and useful Improvements in Miners' Drills, of which the following is such a full, clear, and exact description as will enable others skilled in the art to which it appertains to make and use my said invention.

This invention is a modification and improvement of 10 the invention set forth in United States Patent #762863 granted to me June 14, 1904 for improvement in coal drills.

The purpose of this invention is to simplify the construction of the drill mechanism and to provide improved means for engaging and disengaging the operating parts.

The invention is illustrated in the accompanying drawings to which reference is hereby made and is hereinafter particularly described and finally recited 20 in the claims.

Similar reference letters and numerals designate like parts in the several views.

Figure 1. is an elevation of the gear mechanism for a miner's drill, part of the shell being shown as broken 25 away, to expose inclosed parts. Fig. 2. is a vertical axial section on the line 2. 2. of Fig. 3, on a reduced scale showing a portion of the auger in elevation. Fig. 3. is a vertical transverse section through the drill on the zig-zag line 3. 3. of Fig. 2. Fig. 4. is a transverse 30 section on the line 4. 4. of Fig. 1. and Fig. 5 is an enlarged elevation of the right hand end of the machine.

The shell inclosing the mechanism is of cast iron and comprises a right-hand member A and a left-hand member A' connected together by bolts *a* or equivalent connecting devices.

Trunnions *a*¹ on the members A and A' serve to support the shell on a tripod or other suitable support, not shown.

A circular plate B is intermediate of the members 40 A and A' and is securely connected therewith by the bolts *a* and has in one face a circular groove *b* in which balls *C* travel freely.

The auger D turns within the shell and has longitudinal channels *d* in which internal feathers *e*¹ on the 45 hub *e* fit.

The combined spur and bevel wheel E turns within the shell and has an integral hub *e* accommodating the auger D.

The cog wheel F turns within the member A' and 50 has an integral hub accommodating the auger D and a perforated diaphragm *f* engaging the spiral of the auger and also has in one face a circular groove *f*' accommodating balls *C*' which travel in the groove *f*' and in a corresponding groove in the inner face of the member 55 A'. A shaft G turns and slides in suitable openings *a*²

in the members A and A'. A spur pinion H is secured on the shaft G and has a clutch member *h*. A spur pinion K turns on the shaft G and has a clutch member *k* with which the clutch member *h* of the pinion H engages. Plates M and M' turn on stud screws *m* connecting the plates with the members A and A' respectively and are adapted to lie across the path of the shaft G and limit longitudinal movement of the shaft as hereinafter explained.

In Fig. 2, the plate M is shown lying across the path of the shaft G so as to prevent the moving of the shaft to the right. If the plate M be turned to withdraw it from the path of the shaft the shaft may be slid to the right and the wheel H being fixed on the shaft G the sliding of the shaft to the right will disengage the 65 clutch member *h* from the clutch member *k* and leave the wheel K free to turn on the shaft G. When the shaft is moved to the right as described the plate M¹ will be turned to lie across the path of the shaft at the 70 left hand end of the shaft and will prevent the shaft 75 from again moving to the left until the plate M¹ is removed from the path of the shaft.

When the pinion H is disengaged from the pinion K the latter will be free to turn and permit free turning of the wheel F.

The wheel E and the pinion H and the wheel F and the pinion K are so proportioned that the wheel F will move slightly slower than the wheel E. This difference in speed is attained by giving the pinions H and K the same number of teeth and giving the 85 wheel E one tooth more than the wheel F.

When the pinions H and K are in clutch, the turning of the shaft N will cause the bevel pinion N' to drive the wheel E and the feathers *e*¹ fitting in the channels of the auger D will cause the auger to turn, 90 and the auger will be gradually forced lengthwise through the hubs of the wheels E and F by the diaphragm *f* acting on the spiral of the auger as explained in my Patent #762863.

If it be desired to withdraw the auger, the shaft G 95 will be slid to the right to disengage the pinion K, whereupon if the auger be pulled lengthwise through the hubs of the wheels E and F the longitudinal movement of the auger will cause the turning of the wheel F and the pinion K by reason of the diaphragm 100 *f* sliding on the spiral of the auger, and the wheel F and the pinion K both being free to turn, the auger may be easily and quickly withdrawn.

Balls *C* fitting in the circular grooves of the wheel F and the plate B and the balls *C*' fitting in the circular 105 grooves of the member A' and the wheel F facilitate the turning of the wheels.

The intermediate plate B having a circular groove as described serves a double purpose viz; it accommodates the balls for the ball-bearing and also serves to 110

prevent displacement of the pinion K; that is to say if the wheels H were slid to the right and the clutch member h should stick on the clutch member k the pinion K might be caused to slide to the right out of its proper position, but the pinion K being between the member A' and the plate B, the member A' prevents movement of the pinion to the left and the plate B prevents movement of the pinion to the right.

On the member A is a projecting lug a^3 which supports the free end of the plate M when the plate lies across the path of the shaft G as shown in Fig. 2.

When the drill is in place on the tripod the plate M' gravitates across the path of the shaft G.

If it be desired to move the shaft G to the right to disengage the clutch members of the pinions H and K, the plate M will be turned to withdraw it from the path of the shaft G and the shaft will then be pushed to the right by hand and the plate M' will gravitate across the path of the shaft and prevent the shaft from being moved to the left until the plate M' is again turned out of the way of the shaft.

To move the shaft G to the left and bring into engagement the clutch members of the pinions H and K, this procedure will be reversed.

Having fully described my invention what I claim as new and desire to secure by Letters Patent is;

1. In a miner's drill the combination of shell members, a grooved circular plate intermediate of and secured to

the shell members, a grooved wheel turning within the shell members, and balls fitting in the grooves of the 30 grooved wheel and the intermediate plate.

2. In a miner's drill the combination of connected shell members, a shaft turning and sliding within the shell members, a pinion secured on said shaft and having a clutch member, a pinion loose on said shaft and having 35 a clutch member matching the clutch member of the first named pinion, and plates contiguous to the ends of said shaft and movable to lie across the path thereof.

3. In a miner's drill the combination of a shell, oscillative plates mounted on the shell, a shaft slideable and 40 turnable in the shell, a pinion fixed on the shaft and having a clutch member, a pinion loose on the shaft and having a clutch member matching the clutch member of the first named pinion, and differential gear wheels within the shell coöperating with said pinions respectively. 45

4. In a miner's drill the combination of a shell, an intermediate plate fixed within the shell, a spur wheel turning within the shell between the intermediate plate and one side of the shell, a shaft turnable within and slideable across the shell, a pinion fixed on said shaft and having 50 a clutch member, a pinion loose on said shaft and turning between the intermediate plate and one side of the shell and having a clutch member matching the clutch member of the first named pinion, said intermediate plate serving to prevent sliding of said last named pinion. 55

In witness whereof I have hereunto subscribed my name at Springfield this 31st day of January 1907.

GEORGE F. WEISS.
